DESIGN FOR A HANDLE COVER BRACKET

Frederick F. Pfefferkorn, Washington, D. C.

Application December 27, 1944, Serial No. 117,107

Term of patent 3½ years

(Cl. D58—26)

To all whom it may concern:

Be it known that I, Frederick F. Pfefferkorn, a citizen of the United States, residing at Washington, D. C., have invented a new, original, and ornamental Design for a Handle Cover Bracket, of which the following is a specification, reference being had to the accompanying drawing, forming a part thereof.

Figure 1 is a perspective view of a handle cover bracket showing my new design.

Figure 2 is a side elevation of the bracket. Figure 3 is an end elevational view thereof. Figure 4 is a top plan view thereof.

The broken line representation of a handle and cover member as shown in Fig. 1 is for illustrative purposes only.

I claim:

The ornamental design for a handle cover bracket, as shown and described.

FREDERICK F. PFEFFERKORN.
